Primary Examiner—Prabhakar G. Deshmukh
Attorney, Agent, or Firm—Robert J. Schaap[57] **CLAIM**

The ornamental design for an electronic equipment container, as shown and described.

DESCRIPTION

FIG. 1 is a perspective view of an electronic equipment container showing my new design;
FIG. 2 is a left side elevational view thereof; the right side elevational view being a mirror image thereof;
FIG. 3 is a top plan view thereof;
FIG. 4 is a bottom plan view thereof;
FIG. 5 is a front elevational view thereof; the rear side elevational view being a mirror image thereof;
FIG. 6 is a perspective view of a first embodiment of FIG. 1;
FIG. 7 is a left side elevational view of FIG. 6; the right side elevational view being a mirror image thereof;
FIG. 8 is a top plan view of FIG. 6;
FIG. 9 is a bottom plan view of FIG. 6;
FIG. 10 is a front elevational view of FIG. 6; the rear elevational view being a mirror image thereof;
FIG. 11 is a perspective view of a second embodiment of FIG. 1;
FIG. 12 is a left side elevational view of FIG. 11; the right side elevational view being a mirror image thereof;
FIG. 13 is a top plan view of FIG. 11;
FIG. 14 is a bottom plan view of FIG. 11;
FIG. 15 is a front elevational view of FIG. 11; the rear elevational view being a mirror image thereof;
FIG. 16 is a perspective view of a third embodiment of FIG. 1;
FIG. 17 is a left side elevational view of FIG. 16; the right side elevational view being a mirror image thereof;
FIG. 18 is a top plan view of FIG. 16;
FIG. 19 is a bottom plan view of FIG. 16; and,
FIG. 20 is a front elevational view of FIG. 16; the rear elevational view being a mirror image thereof.
